United States Patent Office

Des. 213,890

Patented Apr. 22, 1969

213,890

GAME BOARD

Charles J. Schultz, P.O. Box 5324, Reno, Nev. 89503

Filed May 31, 1968, Ser. No. 12,159

Term of patent 14 years

Int. Cl. D21—01

U.S. Cl. D34—5

The figure is a plan view of a game board showing my new design. The essential features of my design are shown in full lines. The game board is of conventional thickness.

I claim:

The ornamental design for a game board, as shown and described.
